MOTOR DRIVEN JUMP ROPE

Ronald W. Tannahill, 13658 Rutherford Ave.,
Paramount, Calif.

Filed Dec. 12, 1960, Ser. No. 63,199

Term of patent 14 years

(Cl. D34—5)

FIGURE 1 is a perspective view of a motor driven jump rope showing my new design;

FIGURE 2 is a front elevational view of said motor driven jump rope; and

FIGURE 3 is a side elevational view of said motor driven jump rope.

I claim:

The ornamental design for a motor driven jump rope, substantially as shown.
